FLUID DRIP DISPENSER

Frederick W. Storck, Arlington, Mass., assignor to
 Standard Mailing Machines Company, Everett,
 Mass., a corporation of Massachusetts

Application February 17, 1936, Serial No. 64,214

6 Claims. (Cl. 221—148)

This invention relates to fluid dispensers and more particularly to a dispenser for automatically dripping the fluid at a desired rate of drip discharge or interval sequence.

- 5 In many instances the use of such apparatus requires a measured interval of drip discharge for a specific purpose, such as that required of a lubricant to properly lubricate a bearing, and in another instance, the replenishment of a fluid in 10 a direct proportion to consumption, such as is exemplified by the usual type of stamp affixing and mailing machines wherein each stamp or piece of mail matter requires the application of a predetermined amount of moisture.
- 15 To accomplish these objectives, heretofore fluid reservoirs have been provided with various types of control valves capable of manual adjustment to regulate the discharge from a reservoir as is well known to those skilled in the art.
- 20 To control the drip discharge from a reservoir to a very limited number of drips in a given interval of time requires closely restricted apertures which, due to the characteristics of many fluids, become obstructed and clogged and thus fail to function in an intended manner. Fluid 25 controls of the aforementioned character require frequent attention and clearing of the restricted apertures so that they may function properly.

For example, it is well known that when water 30 is contained within or discharged through a conduit having small restricted openings, the bacteria, such as are usually found in most waters, will adhere to the surface of the conduit and eventually build up and obstruct the passage.

35 Again, many petroleum products, principally utilized as lubricating oils, have characteristics which do not readily lend themselves to close valve adjustments or restricted apertures such as required to limit the drips to a small number 40 in a given interval of time.

Accordingly, one of the objects of my present invention is to provide an automatic fluid drip dispenser wherein the sequence of drip interval may be controlled without the use of the usual 45 regulating valves or extremely small or restricted discharge openings.

Another object of my invention is to provide my fluid drip dispenser with a discharge conduit of a sufficient size to permit the fluid to readily 50 discharge therethrough and whereby each drip discharged will cause a flushing action by the fluid in the conduit.

A further object of my invention is to provide 55 an automatic fluid drip dispenser of a simple and efficient construction that may be readily adjusted to vary the interval sequence of the drips.

With the above and other objects in view, my invention comprises a novel combination and arrangement of parts hereinafter described and

more specifically pointed out in the appended claims.

In the accompanying drawing I have illustrated a preferred form of my invention sufficient to enable those skilled in the art to understand the construction and operation thereof.

Referring to the drawing:

Fig. 1 is a side elevation of my fluid drip dispenser and replenishment reservoir. 10

Fig. 2 is a plan view of my dispenser as illustrated at Fig. 1, but with the replenishment reservoir omitted.

Fig. 3 is a sectional view taken substantially along line 3—3, Fig. 2. 15

Fig. 4 is a sectional view taken substantially along line 4—4, Fig. 2, and

Fig. 5 is an end elevation of the outer end of my discharge conduit.

In this instance I have shown an adjustable 20 supporting bracket 10 which is pivoted at 11 to a suitable table or stationary member 12. The horizontally extending arm 10a of the bracket is provided with a threaded adjusting screw 13 which engages with the member 12. This adjusting screw 13 illustrates one means by which the device may be angularly positioned relative to a horizontal plane for a purpose hereinafter described. 25

The bracket 10 has an enlarged end which is 30 provided with an upwardly extending annular wall 10b adapted to form a supporting chamber for the dispenser base 14.

The dispenser base 14 embodies a chamber 15 having an opening 16 which is adapted to closely engage the depending discharge conduit 17 of a fluid supply reservoir 18. This base 14 is provided with a discharge conduit 19 which is positioned adjacent the bottom of the chamber 15 and extends outwardly therefrom. My illustrated discharge conduit 19 terminates in a flange portion 19a which has a notch 19b formed in its outer face for the purpose of concentrating and directing the discharge from the conduit 19, although this same effect may be accomplished by providing the conduit opening with a depending pointed portion. 40

Positioned above the discharge conduit 19 and communicating with the chamber 15 is an air vent opening 20 which, in this instance, communicates with an air conduit 20a disposed in the wall of the base 14. It is desirable to position the end of the air vent conduit 20a so that it is open to the atmosphere above the air inlet and in my preferred form I have positioned this conduit 20a at substantially right angles to the conduit opening 20 which communicates with the chamber 15. This arrangement prevents possible slopping or spilling of the fluid through the air vent during removal or replacement of 45 50 55 60

the base, although the air vent 20 will function in the desired manner when positioned substantially in a horizontal plane above the discharge conduit 19.

- 5 In the above described device the discharge conduit opening and chamber air vent opening 20 establish a hypothetical horizontal plane and the fluid contained in the chamber 15, below this plane, may be described as subject to atmospheric pressure, and the fluid above this plane, including the replenishment supply, may be described as air-locked. This so-called hypothetical horizontal plane may be conveniently termed a neutral atmospheric pressure plane, as, when 10 15 the discharge conduit opening and chamber air vent 20 are positioned relative to or in this plane, fluid discharge from the device is withheld.
- In the operation of my device the replenishment reservoir 18 is filled with fluid and its discharge conduit inserted into and in close engagement in the open end 16 of the chamber 15. The assembling of the reservoir 18 and base 14 is preferably accomplished with the base 14 removed and the reservoir discharge conduit 17 held in an upright position. While, as stated, 20 25 this is preferable, it is not necessarily essential as it is obvious that the base 14 may be in a fixed position and the filler reservoir discharge conduit inserted into its position.
- 30 When the reservoir 18 and base 14 are in operative position, as shown in the drawing, and the discharge conduit 19 is elevated in the direction of arrow *a*, Fig. 1, the discharge opening of the conduit will eventually be moved to the 35 neutral atmospheric or complete air-locking plane with the air vent opening and the fluid within the chamber 15 will not discharge therefrom. As the discharge opening of the conduit is moved downwardly in the direction of arrow 40 *b*, Fig. 1, relative to the air vent 20, and below the so-called neutral atmospheric pressure plane, the fluid is discharged in drip formation in a 45 direct relation to the angular positioning of the conduit 19 and the lowering of the discharge opening thereof. This relative angular positioning of the conduit 19 and its discharge opening for a given interval of drip discharge is dependent upon the viscosity of the fluid used. A greater or lesser angular positioning of the discharge conduit 19 relative to the air vent is required 50 in a direct relation to the viscosity of the fluid being dispensed.

For example, in tests with water, I have found that, with a discharge conduit opening of .0935" 55 and an air vent opening of .1875" spaced approximately .3437", center to center, above the conduit, the drip discharge will have substantially a minimum interval between drips when the conduit 19 is positioned in a substantially horizontal plane. As the conduit is elevated in the direction of arrow *a*, Fig. 1, above the horizontal plane, the space interval between drips is increased in a direct relation to the elevated 60 position of the conduit, and when the discharge opening of the conduit is elevated up to substantially the plane of the air vent, the fluid will cease to discharge as aforesaid. Conversely, as the conduit angle is lowered in the direction of arrow *b*, Fig. 1, and depends below the horizontal plane, the drip discharge is increased to what 65 might be termed a drip stream, that is, with no interval or space between the drips.

The above proportions are given merely as 70 illustrative and not as limiting my invention.

thereto as it is obvious that these proportions and relationships may be varied for specific conditions as stated without departing from the spirit and scope of my invention.

Having thus described my invention, what I claim is:

1. A variable drip dispenser for fluids comprising a chamber, a normally air-locked fluid supply for said chamber, an air vent in said chamber, a discharge outlet from said chamber and 10 separate from said air vent, said air vent being located at a higher level than said discharge outlet and means for varying the effective pressure head to control the rate of discharge from the outlet. 15

2. A variable automatic drip dispenser for fluids comprising a reservoir having a depending discharge conduit, a chamber adapted to receive said conduit, a second discharge conduit communicating with said chamber, an air vent communicating with said chamber between said first and second discharge conduits and separate from said discharge conduits, and manually adjustable means for varying the effective pressure head whereby the interval of drip discharge 20 25 from the chamber is controlled. 30

3. An automatic drip dispenser for fluids comprising a fluid chamber adapted to receive a volume of fluid, an air vent for said chamber, a barometrically controlled replenishment supply for said chamber, a horizontal discharge conduit separate from said air vent and communicating with said chamber, means for angularly disposing said discharge above the horizontal and means for varying the angularity thereof to control 35 the drip discharge therefrom. 35

4. An automatic drip dispenser for fluids comprising an air-locked fluid reservoir, an air vent in the lower portion of said reservoir, said air vent being so formed that its opening to the atmosphere is disposed substantially above its communicating opening with said reservoir, a discharge conduit disposed below the communicating opening of said air vent and communicating with the fluid in said reservoir, and means for varying the effective pressure head to control 40 45 the rate of drip discharge. 45

5. A drip dispenser for fluids comprising a barometric fluid supply, a chamber disposed substantially below said supply, an air vent communicating with said chamber, a substantially horizontal discharge conduit separate from said air vent and communicating with said chamber, said conduit being substantially of a size that the fluid would normally flow therethrough, with 50 adjustable means adapted to angularly position said conduit above the horizontal and whereby the angular position of said conduit regulates the discharge from said chamber and supply. 55

6. A drip dispenser for fluid comprising a pivoted horizontal bracket carrying a socket provided with a discharge spout, a receptacle fitting within said socket and having a discharge opening therein adjacent the bottom thereof registering with said spout and being provided with a vent communicating with the interior thereof at a point above said discharge opening, a supply reservoir having a neck fitting within said receptacle and being normally airlocked, and means for adjusting the angularity of said bracket above the horizontal to control the rate of drip 60 65 70 discharge. 70

FREDERICK W. STORCK.
